Primary Examiner — Susan Moon Lee**CLAIM**

The ornamental design for a remote dog trainer, as shown and described.

DESCRIPTION

FIG. 1 is a top front perspective view of a remote dog trainer showing my new design;

FIG. 2 is another perspective view of the remote dog trainer at an offset angle with respect to FIG. 1;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view thereof, as labeled with symbol 9 in FIG. 1; and,

FIG. 10 is another partial enlarged view thereof, as labeled with symbol 10 in FIG. 8.

Broken lines and unshaded portions contained within broken lines depict portions of the remote dog trainer that form no part of the claimed design but are shown for purposes of illustration.

1 Claim, 10 Drawing Sheets(56)
